US0D1032360S

(12) **United States Design Patent** (10) Patent No.: **US D1,032,360 S**
(45) Date of Patent: ** Jun. 25, 2024

(54) **CAP**

(71) Applicant: **Johnson & Johnson Consumer Inc.**,
Skillman, NJ (US)

(72) Inventors: **Evan Rhodes**, Brooklyn, NY (US);
Thomas Joseph Zuber, Fort Lee, NJ (US); **Anthony Di Bitonto**, Brooklyn, NY (US); **Stephane Robic**, Val de Reuil (FR); **Olivier Martins**, Val de Reuil (FR); **Christophe Legendre**, Val de Reuil (FR); **Damien Rey**, Saint-Georges-de-Reneins (FR); **Sylvain Verite**, Saint-Georges-de-Reneins (FR)

(73) Assignee: **Johnson & Johnson Consumer Inc.**,
Skillman, NJ (US)

(**) Term: **15 Years**

(21) Appl. No.: **29/810,663**

(22) Filed: **Oct. 7, 2021**

(51) LOC (14) Cl. **09-07**

(52) U.S. Cl.

USPC **D9/453**

(57) **CLAIM**

The ornamental design for a cap, as shown and described.

DESCRIPTION

FIG. 1 is a top perspective view of the cap in accordance with our design;

FIG. 2 is a top end view of the cap in accordance with our design;

FIG. 3 is a first side elevational view of the cap in accordance with our design, the opposite side being the same;

FIG. 4 is a bottom end view of the cap in accordance with our design; and,

FIG. 5 is a front elevational view of the cap in accordance with our design, the opposite side being the same.

In the drawings, the broken lines show portions of a cap that forms no part of the claim.

1 Claim, 3 Drawing Sheets
